[57] CLAIM

The ornamental design for a combine rear panel, as shown and described.

DESCRIPTION

FIG. 1 is a side view of a combine rear panel showing our new design.

FIG. 2 is an enlarged top view of the combine rear panel design of FIG. 1.

FIG. 3 is a left side view of the combine rear panel of FIG. 2.

FIG. 4 is a front view of the combine rear panel of FIG. 2; and,

FIG. 5 is a right side view of the combine rear panel of FIG. 2.

The broken lines immediately adjacent the shaded surfaces represents the bounds of the claim and all other broken lines are for illustrative purposes only. None of the broken lines form part of the claimed design.
